UNITED STATES PATENT OFFICE.

JOHN ESTEN KELLER, JR., OF LITCHFIELD, CONNECTICUT.

INFLATION-VALVE.

No. 834,911.

Specification of Letters Patent.

Patented Nov. 6, 1906.

Application filed July 10, 1905. Serial No. 269,004.

To all whom it may concern:

Be it known that I, JOHN ESTEN KELLER, Jr., a citizen of the United States, residing at Litchfield, in the county of Litchfield and State of Connecticut, have invented a new and useful Inflation-Valve, of which the following is a specification.

This invention relates to inflation-valves for inflatable tires, and has for its object to 10 provide certain new and useful improvements in the valve mechanism whereby the valve element is held against displacement inwardly through the tubular valve-stem by the action of the inflowing air under pump- 15 pressure or by reason of the mechanical unseating of the valve prior to the connection of the device with a pump.

It is also proposed to enable the convenient removal of the valve element from the 20 valve-tube for convenience in making repairs.

A further object is to prevent entire displacement of the rim-engaging element of the stem-fastening means with the dust-cap 25 should these two elements become interlocked.

With these and other objects in view the present invention consists in the combination 30 and arrangement of parts, as will be hereinaftermore fully described, shown in the accompanying drawings, and particularly pointed out in the appended claims, it being understood that changes in the form, proportion, size, and minor details may be made 35 within the scope of the claims without departing from the spirit or sacrificing any of the advantages of the invention.

In the accompanying drawings, Figure 1 is a central longitudinal sectional view of an inflation-valve of the present invention. Fig. 40 2 is a detail sectional view of the valve mechanism removed from the tubular valve-stem. Fig. 3 is a detail cross-sectional view on the line 3-3 of Fig. 2. Fig. 4 is a detail cross-sectional view of the tubular valve-stem on the line 4-4 of Fig. 1. Fig. 5 is a detail view of the follower for preventing removal of the clamping-nut from the tubular stem with the dust-cap. Fig. 6 is a view similar to Fig. 1, 45 showing the valve mechanism in a modified form of stem. Fig. 7 is an elevation of the valve-tube. Fig. 8 is a top plan view of the valve-stem with the valve-tube therein as embodied in Fig. 1. Fig. 9 is a similar view 50 as embodied in Fig. 6.

Like characters of reference designate corresponding parts in each and every figure of the drawings.

The present form of valve includes a tubular open-ended stem 1, which is externally 60 threaded and provided with diametrically opposite flattened faces 2, extending throughout the entire length of the stem. One end of the stem is provided with a head 3 and suitable clamping mechanism 4 to clamp the 65 inner tube 5 of the tire between said clamping means and the head 3, while the remaining portion of the stem passes through the outer tube member 6 of the tire and the rim 7. The tubular stem 1 is internally smooth 70 and counterbored in its outer end portion, so as to provide an internal annular shoulder 8.

For securing the valve-stem to the rim there is a clamping-nut 9 fitted upon the stem and threaded both internally and externally. 75 The lower portion of the nut is provided with an annular enlargement 10, which is serrated upon its peripheral edge to form a finger-piece and is provided in its upper face with an annular channel or seat 11, in which is received 80 a packing-ring 12, which projects above the upper face of the finger-piece. Interposed between the rim and the nut there is a washer consisting of a metallic ring 13, having internal flattened portions to engage the flat 85 faces of the stem, so as to prevent rotation of the washer, and provided at its outer edge with a peripheral flange 14, which projects above the top and bottom of the washer. Packing-rings 15 and 16 are fitted to the upper 90 and lower faces of the washer within the flange 14 and projected, respectively, above and below said flange for engagement by the nut and the rim. When the nut is set down against the washer, the tubular stem 1 is 95 drawn through the nut and the tire and rim thereby clamped between the head 3 of the stem and the nut in a very simple and efficient manner.

The valve mechanism includes an open-ended valve-tube 17, which is provided with an external intermediate annular groove or channel 18 for the reception of a packing-ring 19, which is designed to fit snugly against the internal annular shoulder 8 of the valve-stem 1 when the valve-tube is fitted within the outer open end of the valve-stem. The lower end portion of the valve-tube is internally enlarged, so as to provide a valve-seat 20, which is preferably of inverted conical 100 105 110

shape, the walls of the enlarged portion of the tube being provided with diametrically opposite longitudinal slots 21, and between the slots the walls of the tube are indented or 5 pressed inwardly to form internal shoulders or projections 22. Working endwise within the valve-tube is the valve-stem 23, which is threaded at its upper end, as shown at 24, and carries a cup-shaped valve member 25 at its 10 lower end, there being a suitable packing-ring 26 contained within the cup and designed to bear against the seat 20 when the valve is seated. As clearly indicated in Fig. 2 of the drawings, it will be noted that the 15 internal projections 22 constitute stops to limit the downward movement of the valve, and thereby prevent displacement of the latter through the lower open end of the valve-tube. The upper end of the valve-tube is provided with an internal and externally threaded nipple 27 for engagement with externally and internally threaded pump connections. There is a closure for 20 the open outer end of the nipple consisting 25 of a tubular internally-threaded shank 28, for the reception of the upper threaded terminal 24 of the valve-stem 23, the upper end of the shank being provided with a head 29, adapted to close down tight against the nipple, as clearly shown in Fig. 1 of the drawings. In addition to closing the open top of 30 the valve-tube the element 28 constitutes a valve holder or retainer to mechanically hold the valve seated, by reason of the fact that 35 the valve is drawn up snugly against the seat 20 when the head 29 of the holder engages the nipple and the device is further rotated.

To enable the convenient removal of the valve from the valve-tube, the lower end of 40 the stem 23 is projected below the valve 25, as shown at 30, to afford a finger-grasp, whereby the valve may be forcibly drawn past the 45 projections 22. By preference this projection 30 is threaded in order that the valve holder or retainer 28 may be fitted thereto when the valve-tube has been removed from the tubular valve-stem 1, so as to constitute a handle for more conveniently removing the valve from the valve-tube. It will here be 50 explained that the bifurcating of the inner or lower end of the valve-tube renders the latter elastic to permit of the walls yielding sufficiently to enable the withdrawing of the valve past the projections 22.

55 The valve-tube 17 is retained within the tubular stem 1 by means of a retaining-cap 31, which is internally threaded to embrace the outer end of the stem 1 and is provided at its outer end with an internal annular 60 flange 32 to embrace the outer end of the valve-tube at the base of the nipple 27. To prevent rotation of the valve-tube within the tubular stem, said tube is provided with lateral projections 33, designed to be received 65 within notches or seats 34 in the outer end of

the tubular valve-stem. Similar means are employed to prevent rotation of the valve 25 within the valve-tube 17 and consists of opposite projections 35, which work in the slots 21 of the valve-tube. 70

The members 31 and 29 are housed and protected by means of a tubular cap 36, which is closed at its outer end and embraces the outer end portion of the tubular stem 1, its open end portion being internally threaded 75 for engagement with the externally-threaded portion of the nut 9, the lower end of the cap being designed to bear against the packing-ring 12 of the nut.

As the cap 36 and nut 9 become interlocked by frictional contact and also by rust the nut will be backed off of the stem 1 with the dust-cap. To prevent entire removal of the nut with the dust-cap, there is provided a follower 37 in the nature of a metallic ring 80 loosely embracing the stem 1 between the nut 9 and the retaining-cap 31, the inner edge of the follower being provided with diametrically opposite flattened portions 38 to engage the flattened faces of the stem, and thereby prevent rotation of the washer. In view of the fact that the washer or follower 37 is slidable upon the stem and the nut 9 is rotatable upon the stem independently of the follower, the nut may be tightened 85 against the rim of the wheel without removing the dust-cap 36, the retaining-cap 31, and the follower. Furthermore, should the nut work loose it cannot come entirely off, for the reason that the follower 37 will contact 90 with the retaining-cap 31, and thereby limit outward movement of the nut. 95

In Fig. 6 of the drawings I have shown the valve mechanism hereinbefore described applied to a slightly-different form of tubular stem, which is designated 39, the outer end portion of the stem being reduced, as at 40, so as to receive the retaining-cap 31 and have the outer periphery of the latter lie within the outer periphery of the stem 39, so as to 100 permit of the cap 41 being threaded directly to the stem 39. With this form of stem any approved means may be employed for clamping the same to the tire and rim. 105

Having thus described the invention, what 110 is claimed is—

1. An inflation-valve having a valve-tube provided with a seat, a valve working in the tube in co-operative relation with the seat, and an internal projection upon the tube to prevent displacement of the valve through the open end of the tube, the valve being accessible at one end of the tube and capable of being forced past the retaining-shoulder to remove the valve from the tube. 115

2. An inflation-valve having a valve-tube which is split longitudinally through one end and is provided with an internal valve-seat, a valve working within the split portion of the tube in co-operative relation with the valve- 120

seat, and valve-retaining projections upon the interior of the tube upon opposite parts of the split portion of the tube, the valve being accessible for removal, and the split portion of the tube being yieldable to permit of the valve being forced past the projections.

3. An inflation-valve having a valve-tube provided with an internal valve-seat, a valve working within the tube in co-operative relation with the seat and provided with a threaded valve-stem at one side and a threaded projection at the opposite side, a retaining projection provided upon the interior of the tube for engagement by the valve to prevent displacement thereof, and a threaded valve-holder for engagement with the threaded valve-stem and the adjacent end of the tube to mechanically seat the valve, said holder capable of being removed from the stem and engaged with the threaded projection to form a handle for forcibly withdrawing the valve past the retaining projection and out of the tube.

4. An inflation-valve having an open-ended valve-tube provided in one end with diametrically opposite longitudinal bifurcations and also provided with an internal valve-seat at the inner ends of the bifurcations, the tube being provided with inwardly-pressed projections located between the bifurcations, a valve working in the bifurcated portion of the tube between the retaining projections and the valve-seat, a threaded valve-stem carried by one side of the valve and a threaded projection upon the other side of the valve, and a threaded valve-holder engaged with the threaded valve-stem and bearing against the adjacent end of the tube for mechanically seating the valve, said holder capable of being removed from the stem and applied to the threaded projection to form a handle for forcibly withdrawing the valve past the retaining projections and out of the tube.

5. In an inflation-valve, the combination with a tubular externally-threaded stem, of a rim-engaging nut upon the stem, a dust-cap embracing the stem and threaded upon the nut, a retaining-cap fitted upon the outer end of the stem, and a slidable non-rotatable follower embracing the stem between the nut and the retaining-cap and movable outwardly under the unscrewing action of the nut until stopped by the retaining-cap.

6. In an inflation-valve, the combination with an externally-threaded tubular valve-stem having an external longitudinal flattened face, a rim-engaging nut fitted to the stem, a retaining-cap upon the outer end of the stem, a dust-cap embracing the stem and threaded upon the nut, and a slidable follower loosely embracing the stem between the nut and the retaining-cap and provided with an internal flat face engaging the flat face of the stem to prevent rotation of the washer, said follower being independent of

the nut and also capable of being moved outwardly under the unscrewing influence of the nut until stopped by the retaining-cap.

7. In an inflation-valve, the combination with a tubular externally-threaded stem having an external longitudinal flat face, valve mechanism contained within the stem, a retaining-cap fitted to the outer end of the stem to hold the valve mechanism therein, a rim-engaging nut carried by the stem, a dust-cap threaded upon the nut, and a follower slidably embracing the stem between the nut and the retaining-cap and provided with an internal flat portion engaging the flat portion of the stem, said follower being independent of the nut and movable outwardly thereby under its unscrewing action until stopped by the retaining-cap.

8. In an inflation-valve, the combination with an externally-threaded tubular valve-stem, of a rim-engaging nut carried by the stem, and non-rotatable means carried by the stem independent of and at the outer side of the nut, said means having a limited slidable movement upon the stem to prevent outward displacement of the nut from the stem, the nut being rotatable independently of said non-rotatable means.

9. An inflation-valve having a tubular externally-threaded stem, a rim-engaging nut carried by the stem, a dust-cap threaded upon the nut, and non-rotatable means carried by the stem at the outer side of the nut and independent thereof, said means having a limited slidable movement upon the stem to prevent outward displacement of the nut, and the nut being rotatable independent of the non-rotatable means.

10. An inflation-valve having an externally-threaded tubular stem provided with an external longitudinal flattened portion, a rim-engaging nut carried by the stem, a non-rotatable follower embracing the stem and having a flattened portion engaging the flattened portion of the stem, and an annular stop carried by the stem outwardly from the follower, the nut being rotatable and the follower being movable outwardly under the unscrewing action of the nut until engaged with the stop.

11. An inflation-valve having an externally-threaded tubular valve-stem, a rim-engaging nut carried by the stem, and removable means carried by the stem to prevent outward displacement of the nut including a non-rotatable follower embracing the stem and engaging the nut, the nut and the follower being separately movable to permit tightening of the nut.

12. An inflation-valve having an externally-threaded tubular valve-stem, valve mechanism contained within the stem, a retaining-cap fitted to the outer end of the stem to hold the valve mechanism therein, a rim-engaging nut carried by the stem, and a

non-rotatable follower slidably embracing the stem between the nut and the retaining-cap and independent of the former, the retaining-cap constituting a stop for engagement by the follower to prevent outward displacement thereof, and the nut capable of being tightened without removing the follower.

13. An inflation-valve having an externally-threaded tubular stem, a rim-engaging nut embracing the stem, a non-rotatable follower slidably embracing the stem for engagement with the outer end of the nut, and a stop upon the stem for engagement by the follower to prevent outward displacement thereof, the nut capable of being tightened without disengaging the follower therefrom.

14. An inflation - valve comprising an externally-threaded tubular stem having an external longitudinal flattened portion, a

rim-engaging nut embracing the stem, a non-rotatable follower slidable upon the stem for engagement with the outer end of the nut and provided with an internally-flattened portion to engage the flattened portion of the stem and prevent rotation of the follower, and a stop carried by the stem for engagement by the follower to prevent outward displacement thereof, the nut capable of being tightened without disengaging the follower therefrom.

In testimony that I claim the foregoing as my own I have hereto affixed my signature in the presence of two witnesses.
